INTERNAL-COMBUSTION ENGINE.

1,413,519.

Specification of Letters Patent. Patented Apr. 18, 1922.

Application filed August 5, 1920. Serial No. 401,360.

To all whom it may concern:

Be it known that I, WALTER R. CRIDER, a citizen of the United States, residing at Indianapolis, in the county of Marion and State 5 of Indiana, have invented certain new and useful Improvements in Internal-Combustion Engines, of which the following is a specification.

This invention relates to internal combustion engines, and particularly to the fuel supply means therefor. The object of the invention is to provide means for supplying liquid fuel to an explosive engine, which can be readily adapted to either two-cycle or 15 four-cycle engines, which is simple in construction, which produces a thorough and complete mixture of the hydrocarbon fuel and air, and which will operate successfully with low grade hydrocarbon fuels, such as 20 kerosene, crude oil, or the like.

The invention comprises the construction and arrangement of parts hereinafter described and claimed.

In the accompanying drawings, Fig. 1 represents a sectional elevation through one form of internal combustion engine embodying the invention; Fig. 2 is partly a side elevation and partly a sectional elevation of the fuel supply mechanism, taken on the line 25 2—2, Fig. 1; Fig. 3 is a partial plan view of the engine shown in Fig. 1, and illustrating the rotary pump, throttle valve and fuel reservoir; Fig. 4 is a cross sectional view of the rotary pump, on the line 4—4, Fig. 3; 30 Fig. 5 is a sectional elevation, corresponding to Fig. 1 and illustrating the invention applied to another form of engine; Fig. 6 is a detail sectional elevation, on an enlarged scale, of a fuel supply controlling valve; and 35 Fig. 7 is a similar view of a throttle valve.

The fuel feeding mechanism shown in the drawings can be applied to any type of internal combustion engine, that is, to a two-cycle, four-cycle, or any other arrangement 45 of engine. In Fig. 1 the invention is shown as applied to an ordinary form of four-cycle engine which comprises a cylinder 1 having a chamber therein in which works the engine piston 2, the latter being coupled by the 50 usual connecting rod 3 to a crank 4 on the main crank shaft of the engine. The engine cylinder is provided with the usual exhaust valve 5 controlling the exhaust of the spent gases through the exhaust outlet 6, and with 55 an inlet 7 for the explosive mixture, con-

trolled by an inlet valve 8. 9 represents the usual ignition devices, which may be of any suitable type. The exhaust valve 5 is provided with a rod or stem 10, which is arranged to be operated by a cam 11 on a 60 cam shaft 12. The inlet valve 8, and the ignition devices 9 are both operated in proper timed relation by a cam shaft 13. Shafts 12 and 13 are operated in the usual manner by any suitable mechanical connection to the main crank shaft of the engine, said connection being so proportioned and arranged that the shafts rotate at half the speed of the main crank shaft, to produce the usual Otto cycle. 70

The explosive mixture supplied to the engine is produced in a fuel supply chamber 15 formed within a casing 16 attached to one side of the engine cylinder, a port or passage 17 leading from said chamber to the inlet 75 connection 7 of the engine cylinder.

Liquid hydrocarbon fuel of any suitable or preferred composition, such as kerosene, crude oil, or other low grade fuel, or gasoline, or other high grade fuel, is supplied to 80 the fuel supply chamber by the following mechanism: 20 indicates a shaft, provided with a gear or sprocket 21, by which the shaft is driven in timed relation from the main crank shaft of the engine by any suitable connection, such as chain, gearing or the like. In the particular four-cycle engine illustrated in Fig. 1, the gearing is so proportioned that shaft 20 rotates at half the speed of the main crank shaft. Shaft 20 carries 85 one of the intergeared members 22 of a rotary pump 23, provided with a supply connection 24 to a tank or reservoir 90, for holding a supply of the liquid hydrocarbon fuel. 24^a is a check valve for preventing return of the fuel to the supply tank when the engine is not running. The pump 23 rotates continuously with the main crank shaft and delivers or discharges under pressure a supply of the fuel into a space or passage 95 25 in the pump casing. Shaft 20 extends along the side of all of the several engine cylinders which may be connected in the same battery, and passes through the several casings 16 thereof. Suitable stuffing boxes 26 100 are provided around the shaft where it passes through the several casings 16. The main portion of shaft 20 is hollow or tubular, to form an inner space or chamber 27, which at one end is in communication, 110

through a plurality of circumferentially spaced ports or openings 28, with the passage 25, whereby the liquid hydrocarbon fuel is fed into the tubular shaft. Each of the 5 casings 16 is provided with an inner sleeve or tubular member 29, having a small port 30 therethrough, said port terminating at its upper end in a valve seat 31. The tubular shaft 20 is provided with ports or openings 10 32, one for each of the several engine cylinders, said ports being arranged relatively to each other, so as to move into and out of registration with the several ports 30 in sleeve 29, in the proper order, to thereby 15 supply successive charges of liquid hydrocarbon fuel to the fuel supply chambers 15 within the casings 16 of the several engine cylinders.

The upper portion of each casing 16 is 20 provided with a threaded bore 35, to receive a hollow threaded plug 36. Within said plug is a valve 37, held to its seat 31 by a spring 38. The tension of this spring may be regulated by adjusting the plug 36 in its 25 threaded socket, and the plug can be secured in adjusted position by a lock nut 39.

The side wall of the casing 16, in the form shown in Fig. 1, is provided with one or more large ports or openings 40, through 30 which the air is supplied to form the proper explosive mixture. Within the casing is preferably located a horizontal wall or bridge 41, connecting the sleeve 29 to the side casing wall, so that the air admitted to 35 the fuel supply chamber is forced to travel upwardly and around the fuel inlet port 30, to thereby lap up and vaporize the liquid hydrocarbon as it flows into the chamber and produce an explosive mixture, which is 40 admitted to the engine cylinder.

The operation is as follows: The engine itself operates according to the well known Otto cycle, that is to say, there is a downward working stroke of the engine, at which 45 time all valves are closed, an upward exhaust or scavenging stroke, a second downward stroke, during which mixed fuel and air is drawn or sucked into the engine cylinder, and an upward compression stroke 50 during which the charge is compressed, this cycle being then repeated. The rotary pump 23 operates continuously to deliver a supply of liquid hydrocarbon fuel into the space 27 in the tubular shaft 20. This shaft rotates 55 continuously at half the speed of the main crank shaft. Ports 28 in the sleeve 29, and ports 30 in the shaft 20, are so proportioned and are so arranged, that during the second upward stroke of each piston, when the inlet 60 valve 8 is open, said ports are in registration and passing each other. At this time the pressure of the fuel supply, and the suction of the engine piston lift the valve 37 from its seat, thereby permitting a charge of liquid fuel to flow through the ports 28 and 30

and into the fuel supply chamber. At the same time air is being drawn into said chamber by the engine suction through the air ports 40. The air supply sweeps upwardly around the sleeve 29 and over the supply of fuel being delivered into the fuel supply chamber. The action is rapid, and the fuel is thoroughly vaporized and mixed with the insweeping air. The mixture flows through the port 17 and inlet 7 into the engine cylinder. At the termination of the downward stroke of the piston the inlet valve 8 is closed, and the mixture is compressed in the engine cylinder on the upward compression stroke of the piston, which aids materially in absorption of the fuel by the air.

To regulate the speed and power of the engine a throttle valve is preferably connected to the liquid fuel supply devices. As illustrated, this valve comprises a casing 85 threaded into an opening 43 in the end casing 16, as shown in Fig. 7, to open communication from the fuel supply passage 25 to the space within said valve casing. The valve casing is provided with a cross wall 90 44 having a plurality of circumferentially arranged ports 45 therethrough. The space 46 on the upper side of said wall is provided with a connection 47 leading back to the supply tank or reservoir 90 for holding the 95 liquid hydrocarbon fuel. Journaled in a boss in the end wall of the casing, and projecting through the transverse wall 44, is a shaft 48, having a controlling valve or plate 49 on its inner end. Said plate is provided with a plurality of ports or openings 50, so that communication through the wall 44, between the chambers on opposite sides of 100 said wall can be regulated. Shaft 48 may be operated by a suitable hand lever or the 105 like. When it is desired to throttle the engine, to control its speed, shaft 48 is adjusted to open the ports 45 more or less and thereby return a portion of the liquid hydrocarbon fuel delivered by the pump 23 back 110 into the supply tank or reservoir. A suitable indicator may be attached to the shaft 48, so that it can be placed in the proper position to throttle the engine down to any 115 particular number of revolutions per minute.

The engine may also be provided with an adjustable automatic relief valve, and speed limiting device. This valve is preferably located in a connection 75 leading from the passage 25 back to the fuel supply tank. It 120 comprises a casing 76 having a cross wall provided with an opening forming a valve seat 77 against which seats the valve 78. The latter is held to its seat by a spring 79, the tension of which may be regulated or adjusted by a threaded plug 80. Plug 80 may be set so that the valve will open when the pressure of the fuel supply reaches any predetermined amount. It therefore not only will relieve the system of any excess pres- 125 130

sure but also may be utilized to limit the speed of the engine. The latter depends upon the fuel supply and this may be limited so that any surplus over a given amount will 5 be automatically returned to the supply reservoir through connection 75.

Figs. 5 and 6 illustrate the invention applied to a two-cycle engine of the type shown in my co-pending application filed of even 10 date herewith, Serial No. 401,280, which describes and claims the engine. This engine consists of a cylinder provided with a small bore 51, forming the combustion or explosive chamber, and a large bore 52 forming 15 an air supply chamber. The piston which works in said cylinder is provided with two heads, a small head working in the small bore 51 and a large head working in the large bore 52. In the side wall of the small 20 bore of the cylinder is located a rotary valve 53, which controls both the exhaust of the spent or waste gases from the combustion chamber, and also the main supply of air to the combustion chamber. Said valve is 25 provided with a cross port 54, which in one position opens communication between the ports 55 and 56 leading respectively to the combustion chamber and to the open atmosphere. In another position port 54 30 opens communication between two passages 57 and 58, one communicating with the large chamber 52 and the other with the small chamber 51 of the engine cylinder.

In the end of the cylinder is located an 35 air inlet valve 59, through which air is admitted to the combustion chamber at the time of exhaust of the waste or spent gases, to scavenge the cylinder.

The large portion of the cylinder is provided with an air inlet port 60 in its side wall, to admit air from the open atmosphere to the space or chamber above the large head of the piston at the end of the down or working stroke thereof.

The fuel supply mechanism for this type 45 of engine is substantially the same as that before described. It comprises a casing 16^a, which is secured to the side wall of the small portion of the engine cylinder and 50 is provided with a bridge wall 41^a. The chamber 15^a within said casing is in communication, through two ports 61 and 62, with the bore or chamber 63 of a fuel supply pump, the piston or plunger 64 of which 55 is attached rigidly at its lower end to the large head of the engine piston. The lower end of the pump plunger is reduced, as at 65, to provide free communication through the bore 63 between the large bore 60 52 and port 62 leading to the fuel supply chamber 15. Communication between the bore of the fuel supply pump and the engine cylinder is afforded by a port or passage 66, controlled by a ball valve 67 which 65 is held to its seat by a spring 68, the ten-

sion of which may be adjusted by a threaded member 69.

When the combustion or explosion of the mixture occurs the engine piston and the plunger 64 are forced downwardly. As soon 70 as the port 55 is uncovered there is an exhaust of the waste gases, accompanied by an inrush of air through the scavenging valve 59. At the same time the plunger 64 has uncovered port 61, so that a charge 75 of compressed air and the hydrocarbon fuel absorbed and carried thereby, rushes into the space above the plunger. Air also enters the large chamber 52 above the large head of the piston. As the piston begins 80 to move upwardly port 61 is covered and the charge of explosive mixture above the pump plunger is compressed. The rotary valve has opened communication between 85 passages 57 and 58 and the air trapped above the large head of the piston is forced into the combustion chamber of the engine cylinder. This continues until the rotary valve cuts off communication between said 90 passages and the piston closes the open end of passage 58. Just before the piston reaches the upper limit of its movement the pressure above plunger 64 becomes greater than that within the combustion chamber and valve 67 is lifted and the explosive mixture 95 rushes under pressure into the combustion chamber. At about the same time the reduced portion 65 of plunger 64 uncovers port 62, so that the remaining portion of the air in chamber 52 above the large head 100 of the piston is forced into the fuel supply chamber 15. Fuel is supplied to this chamber through the rotary tubular shaft 20, which is of the same construction and arrangement and operates in the same way as 105 the form previously described, except for the fact that it is driven at the same speed as the main crank shaft.

The fuel supply system described is of simple construction and can be adapted for 110 any type of engine. It will simultaneously supply a number of engine cylinders and the charges of fuel supplied to the cylinders can be easily regulated by means of the throttle valve described. It also enables 115 low hydrocarbon fuel to be successfully used in an internal combustion engine, thereby largely decreasing the cost of operation. The fuel supply is also regulated or controlled by the main crank shaft of the engine, so that as the needs of the engine vary there is a corresponding variation in the fuel supply. The fuel supply can also be proportioned to the particular engine by making 120 the ports in the rotary fuel supply shaft 125 and in the casing sleeve in which it rotates, of the proper size. The arrangement is compact, is not liable to get out of order, and can be installed and maintained at relatively low cost. It may also be readily applied 130

to any existing internal combustion engine. What I claim is:—

- 5 1. A fuel supply system for internal combustion engines, comprising an engine cylinder, a casing having a mixing chamber communicating with said cylinder and a sleeve lying within said chamber, a hollow shaft rotatable in said sleeve, and means for supplying fuel to said shaft, said sleeve and shaft being provided with ports through which the fuel is fed into said chamber from said shaft, and independent means for supplying pure air to said chamber.
- 10 2. A fuel supply system for internal combustion engines, comprising an engine cylinder, a casing having a chamber communicating with said cylinder and a sleeve lying within said chamber, a hollow shaft rotatable in said sleeve, means for supplying fuel to said shaft, said sleeve and shaft being provided with ports through which the fuel is fed into said chamber from said shaft, and a valve arranged to control the flow of fuel through said ports.
- 15 3. A fuel supply system for internal combustion engines, comprising an engine cylinder, a casing having a chamber communicating with said cylinder, a hollow shaft rotatable in said casing, a pump for forcing fuel under pressure into said hollow shaft, said casing and shaft being provided with ports through which fuel is admitted into said chamber, means for admitting air to said chamber, and means for pumping the mixed fuel and air from said chamber into the engine cylinder.
- 20 4. A fuel supply system for internal combustion engines, comprising an engine cylinder, a casing having a chamber communicating with said cylinder, a hollow shaft rotatable in said casing, a pump for forcing fuel under pressure into said hollow shaft, said casing and shaft being provided with ports through which the fuel is fed into said chamber, and a valve in said casing seating to ward said shaft and normally closing said casing port and arranged to be opened by the pump pressure to permit the feed of fuel into said chamber.
- 25 5. A fuel supply system for internal combustion engines, comprising an engine cylinder, a casing having a mixing chamber communicating with said cylinder and provided with a sleeve having a fuel supply port opening into said chamber, a hollow shaft rotatable in said sleeve and provided with a port arranged to move into and out of registration with said sleeve port, and means for supplying fuel to said hollow shaft, and independent means to supply air under pressure to said chamber.

- 30 6. A fuel supply system for internal combustion engines, comprising an engine cylinder, a casing having a chamber communicating with said cylinder and a fuel supply

port, a hollow shaft rotatable in said casing and provided with a port arranged to move into and out of registration with said fuel supply port, means for supplying fuel to said hollow shaft, and a valve in said casing normally closing said fuel supply port and regulating the supply of fuel to said chamber.

70 7. A fuel supply system for internal combustion engines, comprising an engine cylinder, a casing having a chamber communicating with said cylinder and a fuel supply port, a hollow shaft rotatable in said casing, a pump for forcing fuel under pressure through said hollow shaft, said shaft having a port adapted to move into and out of registration with said fuel supply port, and a valve in said casing normally seating toward said shaft and closing said fuel supply port and arranged to control the supply of fuel to said chamber.

75 8. A fuel supply system for internal combustion engines, comprising an engine cylinder, a casing having a chamber communicating with said cylinder, a hollow sleeve in said chamber provided with a fuel supply port, a hollow shaft rotatable in said casing and having a port arranged to move into and out of registration with said sleeve port, means for supplying fuel to said hollow shaft, and a valve within said casing and seating toward said shaft and normally closing said sleeve port.

90 9. A fuel supply system for internal combustion engines, comprising an engine cylinder, a casing having a chamber communicating with said cylinder, a hollow sleeve in said chamber provided with a fuel supply port, a hollow shaft rotatable in said casing and having a port arranged to move into and out of registration with said sleeve port, means for supplying fuel to said hollow shaft, and a valve in said casing normally closing said sleeve port and arranged to control the supply of fuel to said chamber.

95 10. A fuel supply system for internal combustion engines, comprising an engine cylinder, a casing having a chamber communicating with said cylinder, a hollow sleeve in said chamber provided with a fuel supply port, a hollow shaft rotatable in said casing and having a port arranged to move into and out of registration with said sleeve port, a pump for forcing fuel through said hollow shaft, and a yielding valve in said casing normally closing said sleeve port and arranged to yield under the pressure of said pump for admitting fuel from said shaft into said chamber.

100 11. A fuel supply system for internal combustion engines, comprising an engine cylinder, a fuel supply reservoir, a casing having a chamber communicating with said cylinder, a pump having connections for supplying fuel from the fuel supply reservoir to

- said chamber, a feeding pump for delivering fuel from said chamber to the engine cylinder and having a piston arranged at intervals to cut off communication between said 5 chamber and cylinder, and a throttle valve arranged when open to return a portion of the fuel from the connection between the pump and chamber to the fuel supply reservoir.
- 10 12. A fuel supply system for internal combustion engines, comprising an engine cylinder, a fuel supply reservoir, a casing having a chamber communicating with said cylinder, a hollow shaft rotatable in said casing, 15 said casing and shaft having ports arranged to move into and out of registration with each other, a pump for supplying fuel from the fuel supply reservoir to said hollow shaft, a feeding pump for delivering fuel 20 from said hollow shaft to the engine cylinder and having a piston arranged at intervals to cut off communication between said hollow shaft and cylinder, and an adjustable throttle valve in the connection between said 25 pump and shaft for returning a portion of the fuel supplied by said supply pump to the fuel supply reservoir.
13. A fuel supply system for a battery of internal combustion engines, comprising a 30 plurality of engine cylinders, a plurality of casings, each casing having a chamber communicating with one of the engine cylinders, and a hollow sleeve within said chamber, means for admitting air to said chambers, a 35 hollow shaft extending through and rotatable in said sleeves, said sleeves having ports, and said shaft having ports arranged to move into and out of registration with said sleeve ports, and means for supplying fuel 40 to said hollow shaft.
14. A fuel supply system for a battery of internal combustion engines, comprising a plurality of engine cylinders, a plurality of 45 casings, each casing having a chamber communicating with one of the engine cylinders and being provided with an inner hollow sleeve, means for admitting air to the several chambers independently of each other, a hollow shaft rotatable in the sleeves of said casings, said sleeves and hollow shaft being 50 provided with ports arranged during the rotation of said shaft to open communication successively from said shaft to the several chambers, and means for supplying fuel to 55 said shaft.
15. A fuel supply system for internal combustion engines, comprising an engine cylinder, a casing having a chamber communicating with said cylinder and a fuel supply port, a rotatable hollow shaft provided with 60 a port arranged to move into and out of registration with said fuel supply port, means for supplying fuel to said hollow shaft, and a valve normally closing said fuel port and regulating the supply of fuel 65 to said chamber.
16. A fuel supply system for internal combustion engines, comprising an engine cylinder, a casing having a chamber communicating with said cylinder and a fuel supply 70 port, a rotatable hollow shaft, a pump for forcing fuel under pressure into said hollow shaft, said shaft having a port adapted to move into and out of registration with said fuel supply port, and a valve normally seating toward said shaft and closing said fuel supply port and arranged to control the 75 supply of fuel to said chamber.
- In witness whereof, I have hereunto set my hand and seal at Indianapolis, Indiana, 80 this 28th day of July, A. D. nineteen hundred and twenty.
